UNITED STATES PATENT OFFICE.

ANTON LORENZ, OF WEST NEW YORK, NEW JERSEY.

WINDOW.

SPECIFICATION forming part of Letters Patent No. 700,956, dated May 27, 1902.

Application filed September 11, 1901. Serial No. 75,009. (No model.)

To all whom it may concern:

Be it known that I, ANTON LORENZ, a citizen of the Empire of Austria-Hungary, residing in West New York, in the county of Hudson and State of New Jersey, have invented certain new and useful Improvements in Windows, of which the following is a specification.

This invention relates to a combined window-casing and window-frame in which the frame is adapted to open and close with the sashes, so as to facilitate the cleaning of the latter; and it relates, further, to means for facilitating the raising and lowering of the sashes in the frame.

15 The objects of the invention are to provide a window-casing with a window-frame which is hinged to the casing at one side in order that the frame can be swung open, said frame carrying the sashes; next, to provide means 20 for raising or lowering the sashes while the frame is either open or closed by suspending each sash in the window-frame by means of a single sash-cord, which is attached at its ends to the opposite sides of the sash and passing 25 over suitably-arranged pulleys to a counterbalancing-weight adapted to slide in a recess provided in the exterior side of the stile of the casing.

30 This invention consists of a window comprising a casing to which is hinged the window-frame, sliding sashes in said frame, and means for suspending each sash, consisting of a single cord, a counterbalancing-weight having a pulley, and a plurality of pulleys suitably arranged on the window-frame and in the stile of the casing, so as to balance the sashes whether the window-frame is in open or closed position.

35 The several novel features of construction and combination of parts will be fully described hereinafter and set forth in the claims, reference being had to the accompanying drawings, in which—

40 Figure 1 is a front elevation of the invention, showing the upper sash partly lowered and the sash-suspending mechanism in dotted lines. Fig. 2 is a vertical transverse section of the same on line 2 2, Fig. 1. Fig. 3 is a horizontal section view on line 3 3, Fig. 1. 45 Fig. 4 is an enlarged view of the top of the window-frame with the casing in section in order to show the pulleys and the sash-cords; and Fig. 5 is a perspective view of the upper corner of the window-casing and frame, drawn on an enlarged scale, showing the window-frame in open position.

55 Similar letters of reference designate corresponding parts.

Referring to the drawings, A designates the window-casing, which is set in the wall of the 60 building in the usual course of construction and has hinged thereto at one side the window-frame B, adapted to swing open. The frame is approximately the same thickness as the casing and adapted to fit with sufficient 65 tightness into the rabbeted casing in a manner best adapted to insure a comparatively air-tight contact. The usual ways V are provided in the sides of the frame B for the sliding of the sashes C, each sash being suspended 70 by a novel arrangement of guide-pulleys, sash-cord, and weight.

75 The suspension device consists of a counterbalancing-weight D, adapted to move in the recessed exterior side of the casing A', upon which the frame B is hinged, a sash-cord c, attached at each end to the opposite sides of the sash, and passes over a plurality of pulleys mentioned and located as follows: the pulley d in the counterbalance-weight D, 80 twin pulley E in the side A' of the casing, the pulleys b, provided in the hinged side of the frame opposite the twin pulleys and the pulleys arranged on the top of the frame B adjacent the sides, the pulley b', and the guide-pulley b''. The guide-pulley b'' is mounted vertically on the frame top adjacent the hinged side thereof. The twin pulley consists of two pulley-wheels which are mounted one above the other in the oscillating pulley-box E', that 90 is provided at the top and bottom near corresponding edges with pivots e, which are received in a housing F, secured stationary into a recess of the side A' of the casing. In order to provide for the oscillating movement 95 of the pulley-box E', the housing F has one of its sides diverging, as shown at F' in Figs. 4 and 5. The lower pulley-wheel of the twin pulley is arranged on the same level with the pulley b in the side of the frame and the upper pulley on the same level with the pulley b' in the top of the window-frame. The sash-

100

cord is of double length, doubling around the pulley d of the counterbalance-weight, each length passing over one of the pulley-wheels of the twin pulley. One length passes over 5 the lower pulley-wheel of the twin pulley and over the pulley b' in the side of the window-frame to a suitable attachment in the adjacent side of the sash and the other length of the cord passing from the upper pulley-wheel 10 of the twin pulley around the horizontal guide-pulley b^2 , along the top of the frame, over the pulley b' , to the opposite side of the sash. The hinged window-frame is provided at 15 its opposite side with a suitable knob, by which 15 the same can be readily opened or closed, it being fitted with sufficient tightness into the rabbeted casing and window-sill.

When the window-frame is placed in open 20 position at right angles to the casing, which 20 is the most convenient position for cleaning both sashes on opposite sides, it is necessary that the sash cords and weight respond to the movement of the frame into its inward or open position and again when the same is moved 25 into its normal or closed position. The twin pulleys, with their oscillating boxes and housings, are preferably arranged in the left-hand stile of the window-casing and serve for the purpose of permitting free movement of the 30 window-frame into open or closed position. The suspension device referred to facilitates also the raising and lowering of the sashes when cleaning them without the necessity of sash pulleys and weights at the opposite side 35 of the casing, which could not be arranged conveniently in connection with a hinged and movable window-frame. The sash-weights are preferably of flat shape and of double the weight of the usual sash-weights, and in 40 the present case one weight has to counterbalance the entire weight of the sash, which heretofore was accomplished by two weights. In the same manner one single sash-cord is sufficient for raising or lowering each sash, 45 said sash-cord being arranged as described in connection with the twin pulley in the casing and the guide-pulleys on the window-frame. The improved construction facilitates, therefore, not only the raising or lowering 50 of the sashes in the usual manner when the window-frame is in its normal position in the casing, but it also permits the raising and lowering of the sashes when the window is in inward or open position ready for cleaning 55 the sashes. Without the oscillating pulley-boxes the cords would be strained and subjected to frictional wear, which would be objectionable for various reasons. By the play of the boxes, however, the twin pulleys 60 readily adjust themselves in proper position for facilitating the easy motion of the sash

cord and weight whatever be the position of the window-frame relatively to the casing.

Having thus described my invention, I claim as new and desire to secure by Letters 65 Patent—

1. In a window, the combination, with a window-casing, a window-frame fitting into said casing and hinged at one side thereto, 70 slideable sashes arranged in said frame, and means for suspending each sash, consisting of guide-pulleys located respectively in the window-casing and on the window-frame, sash-weights and single sash-cords attached at their ends to opposite sides of the sashes 75 and guided over the pulleys of the casing and frame, substantially as set forth.

2. In a window, the combination, with a window-casing, of a window-frame hinged at one side to said casing, slideable sashes in said 80 frame, and means for suspending said sashes, consisting of pulleys suitably arranged on said frame, coöperating twin pulleys arranged in said window-casing, sash-cords passing over said pulleys, and counterbalancing- 85 weights for suspending said sashes, substantially as set forth.

3. In a window, the combination, with a window-casing, a window-frame hinged at one side to said casing, slideable sashes in said 90 window-frame, pulleys arranged on the top of said frame adjacent each side, pulleys arranged in the hinged side of the frame adjacent the top thereof, coöperating twin pulleys provided in the window-casing opposite 95 the last-mentioned pulleys in the frame, counterbalancing-weights provided with guide-pulleys and sash-cords passing over the pulleys of the weight, casing and frame, and being attached to the opposite sides of the 100 sashes, substantially as set forth.

4. In a window, the combination, with a window-casing, of a window-frame hinged at one side to said casing, slideable sashes in said frame, suitable pulleys arranged in the top 105 and side of said frame, twin pulleys arranged in said window-casing, a box for housing said pulleys and journaled one above the other therein, a stationary housing in said casing, one side of said housing diverging from the 110 pivotal center of the pulley-box, counterbalancing-weights, one for each sash, and a single sash-cord guided over pulleys and adapted to suspend each weight and sash, substantially as set forth.

In testimony that I claim the foregoing as my invention I have signed my name in presence of two subscribing witnesses.

ANTON LORENZ.
